UNITED STATES PATENT OFFICE

148,911

DESIGN FOR A LADLE

Ernest J. Comeau, Plattsburg, N. Y.

Application August 16, 1946, Serial No. 132,572

Term of patent 14 years

(Cl. D44—29)

To all whom it may concern:

Be it known that I, Ernest J. Comeau, a citizen of the United States, residing at Plattsburg, in the county of Clinton and State of New York, have invented a new, original, and ornamental Design for a Ladle, of which the following is a specification, reference being had to the accompanying drawing, forming a part thereof.

Figure 1 is a perspective view of a ladle showing my new design.

Figure 2 is a side view.

I claim:

The ornamental design for a ladle, as shown.

ERNEST J. COMEAU.
